CABLE CONNECTER

George R. Tarbox, Troy, N. Y.

Application July 25, 1932, Serial No. 624,633

2 Claims. (Cl. 287—78)

It is frequently desirable, particularly in cable guide rails for highways, to secure together the adjacent ends of severed cables.

The principal object of my invention is the provision of a device of the foregoing character which can be cheaply manufactured, which can readily be assembled, and which effectively holds the adjacent ends of the cable in assembled relation.

10 Another object is to provide a cable splice or connector which will have a substantially smooth exterior surface tapering or merging more or less gradually with the surface of the cable itself.

My invention will best be understood by reference to the accompanying drawing in which I have illustrated a preferred embodiment thereof and in which—

Fig. 1 is a disassembled view of two sections of the cable connector embodying my invention;

20 Fig. 2 is a view similar to Fig. 1 but illustrating the relative position of the parts at one stage of the assembly;

Fig. 3 is a perspective view illustrating the cable connector in assembled position;

25 Fig. 4 is a longitudinal section through Fig. 3; and

Fig. 5 is a transverse section taken along the line 5—5 of Fig. 4.

Like reference characters indicate like parts 30 throughout the drawing.

Referring to the drawing, 10 indicates generally a cable connector embodying my invention and comprising two hollow sections, 10a and 10b, which may conveniently be formed of malleable iron or other suitable material. The two sections are preferably identical in construction and are reversible so that the description of one will suffice for both.

The section 10a is, in the embodiment illustrated, provided with a conical passage 11 in which is received the end of a cable 12 shown as comprising three strands. The end of the cable is shown in Fig. 1 as severed at 13. The ends of two adjacent cables are secured within the respective sections, 10a and 10b, in any desired manner. In the embodiment illustrated, the end of one cable is secured in section 10a by a wedge 14 which is provided with longitudinally extending grooves 15 in which the respective strands 50 of the cable are received and which, when wedged between the strands, secures the end of the cable in position. It is to be understood, however, that the end of the cable may be secured within a section of the cable connector 55 by molten metal or by any other suitable means,

In accordance with my invention, the end of each section is provided with forwardly or axially extending lugs 16 here shown as three in number, each lug being provided with an enlarged end 17; a shoulder 18 being provided between the enlarged end 17 and the contracted portion 19 of the lug. Openings 20 are provided between the lugs of a given section for the reception of the complementary lugs of the other section, it being understood that the openings 65 of the given section conform in size and shape to the lugs of the other section.

One of the lugs as 16a is preferably narrower than the remaining lugs and is received in an opening 20a of the other section which is correspondingly narrower than the other openings 70 of the complementary section. The lug 16a is beveled on its outer portion and at the end as at 21. Preferably the lug 16b on the other section and which is diametrically opposite to the lug 16a is likewise beveled at 21 to form a recess, 22, when the unit is in the assembled position indicated in Fig. 4.

The two sections may readily be assembled by inserting one of the lugs as 16b of one section in the opening formed within the lugs of the other section 10a, the other lugs of section 10b being located outside of the lugs of the other section in the manner indicated in Fig. 2, it being understood that the one section is laterally offset from the other when the parts are to be assembled. Then by lifting the lug 16b of section 10b into the opening 20a of the other section, the remaining lugs of section 10b will slip into position within the complementary 90 openings of the other section and the two sections will form a substantially continuous outer surface preferably cylindrical in cross section, as illustrated, the enlarged ends of the lugs of one section being received in the corresponding enlarged portions of the openings of the other section, the lugs of the two sections thus forming an interlocking engagement which prevents longitudinal displacement of the one section with respect to the other. Preferably 100 the interlocking portions of the two sections form a cylinder as indicated at 23.

The two sections are conveniently held in interlocking engagement by a sleeve 24 which forms a fairly close fit over the cylindrical portion 23 of the two sections thereby holding the two sections in interlocking engagement.

The sleeve 24 may conveniently be secured in position by upsetting or depressing a portion of the metal of the sleeve into the recess 22 by the 11

use of a suitable tool. The opposite edge of the sleeve 24 is also depressed into the recess 22 of the other section thereby securely holding the sleeve in position around the interlocking portions of two sections. By forming one of the lugs on one of the sections, and a diametrically opposite lug on the other section, narrower than its associated lugs, and correspondingly forming the openings in which they are received, it is necessary in order to assemble the two sections that the beveled lug on the given section be diametrically opposite to the beveled lug on the other section, so that when metal on opposite sides of the sleeve is upset into the recesses 22 the sleeve is effectively secured in position over the interlocking portions of the two sections.

While I have described my invention in its preferred embodiment, it will be understood that the words which I have used are words of description rather than of limitation and that changes within the purview of the appended claims may be made without departing from the true scope and spirit of my invention in its broader aspects.

25 What I claim is:

1. A connector comprising two sections each provided at its end facing the other section with

a plurality of axially extending lugs having enlarged end portions circumferentially spaced to receive therebetween the lugs of the other section in closely interfitted and interlocked relation, whereby both relative axial and rotative movement of said sections, when assembled, is prevented, one lug on each section being somewhat smaller than the other lugs thereon, whereby said sections may be assembled by a relative lateral movement; and means circumferentially engaging said lugs, when interfitted, to prevent lateral displacement thereof.

2. A connector comprising two substantially identical sections each provided with a plurality of axially extending lugs having enlarged extremities and circumferentially spaced to receive therebetween the lugs of the other section in closely interfitted and interlocked relation, whereby both relative axial and rotative movement of said sections, when assembled, is prevented; at least one of said lugs on each section being narrower than the other lugs thereon whereby said sections may be assembled by relative lateral movement; and a sleeve about said lugs for preventing relative lateral movement when assembled.

GEORGE R. TARBOX.
